(57) **CLAIM**

The ornamental design for an automobile, as shown and described.

DESCRIPTION

FIG. 1 is a front perspective view of an automobile showing our new design;

FIG. 2 is a driver side rear perspective view thereof;

FIG. 3 is a passenger side rear perspective view thereof;

FIG. 4 is a left side view thereof;

FIG. 5 is a right side view thereof;

FIG. 6 is a front view thereof; and,

FIG. 7 is a back view thereof.

It will be understood that the broken lines shown in the drawings illustrate portions of the automobile that form no part of claimed design.
